UNITED STATES PATENT OFFICE.

STEPHEN J. MEEKER, OF NEWARK, NEW JERSEY.

DESIGN FOR A LOCOMOTIVE-TENDER COUPLING.

SPECIFICATION forming part of Design No. 30,682, dated May 2, 1899.

Application filed April 10, 1899. Serial No. 712,537. Term of patent 14 years.

To all whom it may concern:

Be it known that I, STEPHEN J. MEEKER, a citizen of the United States, and a resident of Newark, Essex county, State of New Jersey, have invented and produced a new and original Design for Locomotive-Tender Couplings, of which the following is a specification, reference being had to the accompanying drawings, forming part thereof.

10 In the accompanying drawings, Figure 1 is a plan view of a tender-coupling embodying my new design; and Fig. 2 is a rear end view of the same, looking in the direction indicated by the arrow in Fig. 1.

15 As shown in the drawings, the leading or material feature of my design consists of a

tender-coupling having a shoulder 1, extending in a curved line across the rear of the head 2, and a rearwardly-extending shank 3, which gradually decreases in width from the 20 head toward its rear and narrowed end 4.

Having thus described my invention, what I claim as new, and desire to secure by Letters Patent, is—

The design for a locomotive-tender coupling, substantially as herein shown and described.

STEPHEN J. MEEKER.
